INVENTOR,
John H. White,
By J. B. Lawyer

Attorney.

UNITED STATES PATENT OFFICE.

JOHN H. WHITE, OF NORTH EAST, MARYLAND.

RAZOR-STROP.

SPECIFICATION forming part of Letters Patent No. 294,830, dated March 11, 1884.

Application filed January 17, 1884. (No model.)

To all whom it may concern:

Be it known that I, JOHN H. WHITE, a citizen of the United States, residing at North East, in the county of Cecil and State of Maryland, have invented certain new and useful Improvements in Razor-Strops; and I do declare the following to be a full, clear, and exact description of the invention, such as will enable others skilled in the art to which it applies to make and use the same, reference being had to the accompanying drawings, and to the letters and figures of reference marked thereon, which form a part of this specification.

Figure 1 is a side view of a razor-strop provided with my improvement. Fig. 2 is a side view at right angles to the view in Fig. 1; Fig. 3, a central section in a plane indicated by the line *x* *x* in Fig. 1; Fig. 4, a transverse section in a plane indicated by the line *y* *y*, Fig. 1; Fig. 5, a transverse section in a plane indicated by the line *z* *z*, Fig. 1.

Like letters designate corresponding parts in all of the figures.

In the drawings, A represents the body or hone part of the razor-strop; B, a strop-belt stretched lengthwise on two sides of the main part and at some distance therefrom; and C, the handle. The belt is doubled over and secured fast to the outer end, *a*, of the wooden body A, there being side projections or flanges, *b* *b*, over which the belt is stretched to hold the belt away from the body. The ends of the belt at the other side of the strop are secured to a nut-plate, D, in which a screw-shank, E, in the handle screws, substantially as shown.

The belt need not be separately secured to the nut-plate; the screw-shank holds it securely. At this end of the strop the belt is stretched over a metallic plate, G, screwed or riveted to the end of the wooden body A, as seen in Fig. 4, and having its edges project beyond the sides of the body, as shown, to keep the belt at the proper distance. There is a hole, *c*, in the center of this plate, in which the end *d* of the screw-shank E enters, there being a shoulder; *f*, on the screw-shank to bear against the plate G, for stretching the belt by the action of the screw on turning the handle. It is this plate G and the construction of the same with the shouldered screw-handle C and nut-plate D that constitutes my invention. The construction is very strong, durable, light, and cheap. The plate G, being not so wide as the hone-body A, as shown in Fig. 4, also leaves the hone entirely unimpeded when honing a razor, and the said hone is made easily and cheaply from a simple rectangular piece of wood.

I claim as my invention—
The combination of the plate G, rigidly secured to and projecting beyond the body A, nut-plate D, and handle C, provided with the shouldered screw-shank E, substantially as and for the purpose herein specified.

In testimony whereof I affix my signature in presence of two witnesses.

JOHN H. WHITE.

Witnesses:

ANDREW ANDERSON,
HARRY T. GRANT.
